DESIGN FOR A NIGHT LAMP OR SIMILAR ARTICLE

Edwin W. Harman, Columbus, Ohio

Application September 21, 1948, Serial No. 148,676

Term of patent 14 years

(Cl. D48—20)

To all whom it may concern:

Be it known that I, Edwin W. Harman, a citizen of the United States of America and a resident of Columbus, in the county of Franklin and State of Ohio, have invented a new, original and ornamental Design for a Night Lamp or Similar Article, of which the following is the specification, reference being had to the accompanying drawing, forming a part thereof.

Figure 1 is a side elevational view of a night lamp or similar article, showing my new design; and

Figure 2 is a perspective view thereof.

I claim:

The ornamental design for a night lamp or similar article, substantially as shown.

EDWIN W. HARMAN.
